UNITED STATES PATENT OFFICE.

JOHN A. EKELUND, OF MINNEAPOLIS, MINNESOTA, ASSIGNOR OF ONE-HALF TO
JAMES F. WILLIAMSON, OF MINNEAPOLIS, MINNESOTA.

TOY BASE-BALL-GAME APPARATUS.

959,427.

Specification of Letters Patent. Patented May 24, 1910.

Application filed March 10, 1909. Serial No. 482,451.

To all whom it may concern:

Be it known that I, JOHN A. EKELUND, a citizen of the United States, residing at Minneapolis, in the county of Hennepin and 5 State of Minnesota, have invented certain new and useful Improvements in Toy Base-Ball-Game Apparatus; and I do hereby declare the following to be a full, clear, and exact description of the invention, such as 10 will enable others skilled in the art to which it appertains to make and use the same.

My invention has for its object to provide an improved toy ball game apparatus, and to this end, it consists of the novel devices 15 and combinations of devices hereinafter described and defined in the claims.

This improved toy ball game apparatus is capable of many modifications and different arrangements adapting it to be used in various different kinds of ball games, but in 20 the drawings, it is shown as designed and arranged for playing baseball, very closely in accordance with the ordinary rules of baseball. In this preferred arrangement, 25 the toy device comprises a so-called field plate and toy figures representing pitcher, catcher, batter, baseman and fielders. The field plate is provided with a marginal flange which serves to inclose a diamond, bases and 30 field zones, marked or otherwise formed on the said field plate. The pitcher and the batter are movably mounted and are provided with independently operated actuating devices, and the pitcher is adapted to 35 throw a ball to the catcher, and the batter carries a bat with which he may strike the pitched ball, when moved at the proper time in respect to the throwing of the ball by the pitcher. The baseman and the fielders which 40 are minor features of the device, are preferably simply fixed toy figures representing men.

In the accompanying drawings which illustrate the improved device as above generally outlined and as designed for playing baseball, like characters indicate like parts throughout the several views.

Referring to the drawings: Figure 1 is a perspective view, showing the complete device, some parts being broken away; Fig. 50 2 is a left side elevation of the batter; Fig. 3 is a left side elevation of the pitcher; Fig. 4 is a right side elevation of the lower portion of the batter and actuating device there- 55 for; Fig. 5 is a horizontal section taken on

the line $\alpha^5 \alpha^6$ of Fig. 4; Fig. 6 is a right side elevation, showing the lower portion of the pitcher and actuating mechanism therefor; Fig. 7 is a horizontal section taken on the line $\alpha^7 \alpha^8$ of Fig. 6; and Fig. 8 is a front 60 elevation of the catcher.

The field plate or board 1 is provided with a marginal upwardly extended flange 2, which confines the ball in its movements upon the board 1. This flange 2 at one side 65 of the board, is shown as reduced in height as shown at 2^a , so as to afford more ready access to pitcher and batter controlling devices, presently to be described. The diamond is marked off on the board 1 by four 70 small rods or straight wires 3, secured in rectangular arrangement on said board by any suitable means such as staples 4. The bases 5 are marked on the board at the four 75 angles of the diamond 3. The field is subdivided into zones a , b and c , by means of small rods or straight wires 6 and 7, preferably secured to the board 1 by staples 8.

The bodies of the pitcher, catcher, batter, 80 baseman and fielders, are indicated respectively by the numerals 9, 10, 11, 12 and 13, and they are all preferably made from sheet metal stamped in the form of miniature men. The catcher, the baseman and the fielders are all shown as permanent figures, having 85 base plates screwed or otherwise rigidly secured to the board 1, and all occupy appropriate positions. Also as shown, there is a similar permanently fixed figure 14 representing a short-stop. The catcher 10 is provided with a pair of arms 15 pivoted thereto at 16, and formed with very large hand plates 17 that afford a basket-like receptacle, large enough to receive and to hold a ball 18 which is thrown by the pitcher. The 90 arms 15 are made pivotally adjustable, so that they may be properly set to catch the ball, and the pivot joint 16 is set under such friction, that the arms will not be moved from their set position by the impact of the 95 ball. Furthermore, the said arms are adapted to spring laterally and permit the ball to be forced downward from between the hand plate 17 when the ball is pressed by a finger of the manipulator. 105

The pitcher is under spring tension to move forward, and the body thereof is provided with a pair of arms, one of which is arranged to throw the ball. This throwing arm 19 has a hand formed to receive and 110

hold the ball, as shown in Figs. 1 and 3. At its lower extremity, the body 9 of the pitcher, is provided with a disk-like portion 20, that is pivotally connected by a bolt 21 to a bearing bracket 22, the base of which latter is rigidly secured to the field plate 1. On the bolt 21 is a coiled torsion spring 23, one end of which is anchored to the bracket 22, and the other end of which reacts against the leg 10 portion of the body 9, and exerts a force which tends to throw the said body 9 forward or toward the batter and catcher. When the pitcher is set in a retracted position, ready to throw the ball when released, it is there held by a latch 24, the free end 24^a of which engages a projection 25 of the disk-like portion 20 of the pitcher body 9. This latch 24 is shown as pivoted to the base of the bracket 22, and it is yieldingly held 20 in its operative position by a light coiled spring 26 attached at one end to said bracket, and at its other end to an arm of the said latch 24. Another arm of said latch is connected to one end of a light wire or tripping connection 27, the other end of which as shown, is connected to a latch releasing lever 28, preferably pivoted to the field plate 1, close to the reduced side portion 2^a.

As is evident, when the pitcher is set in 30 its retracted position, as above described, and the latch 24 is moved into its inoperative position by movement of the releasing lever 28, toward the reduced wall 2^a, said pitcher will be released, and the forward 35 movement imparted thereto by the spring 23, will throw the ball past the batter, over the home plate or base, and into the hands of the catcher. The pitcher's throwing arm 19 is preferably made adjustable by pivotal 40 connection to the body 9, which pivotal connection is under such friction that it will not be accidentally moved from its set adjustment in respect to the said body 9. This pivotal adjustment however, may be forced, and the 45 said arm may be so set that the ball will be thrown into the hands of the catcher.

The free end 24^a of the latch 24 is preferably beveled on its upper edge, so that the lug or projection 25 will be automatically 50 cammed into engagement with the said latch when the pitcher is forced backward into its retracted position.

The body 11 of the batter is rigidly secured to a disk-like base 29, that is pivotally 55 connected by a bolt 30 to a bearing plate 31 secured to the field plate 1. Also the said body 11 is provided with arms 32 that are rigidly secured to a bat 33. The arms 32 are 60 preferably pivotally connected to the body 11 by pivot joints which are under such friction, that the said arms and hence the bat, will not accidentally be forced from any set position, but may nevertheless be forced so 65 that the bat may be set at the proper elevation to hit the pitched ball. The striking

movement is imparted to the batter by a suitable spring, preferably in the form of a coiled torsion spring 34, shown as applied around the pivot bolt 30, with one end anchored to the bearing plate 31, and the other pressing against a lug 35 of the rotary disk-like base 29. By a suitable latching and tripping device, the batter is held in a set position with the bat 30 turned away from the pitcher, and with the impelling spring 34 under tension. This latching and tripping device may take different forms, but as shown, it comprises as follows: An intermediate lever 36 is pivotally connected to the bearing plate 31, and is connected by a light chain or flexible connection 37 to the lug 35 of the rotary base 29. The end of the lever 36 is also connected by a light wire 38 to a small lever 39, that is pivotally connected to the field plate 1, close to the reduced side wall 2^a. This lever 39 is provided with an up-turned free end 40, which serves as a finger piece, and this is adapted to be engaged by a laterally projecting lug of a latch lever 41, which in turn is pivotally connected to the field plate 1, and is subject to a light coiled spring 42, which serves to yieldingly hold the said two levers 39 and 40 engaged.

When the finger is engaged with the end 40 of the lever 39, and the latter is moved in the direction of the arrow marked thereon in Fig. 1, the batter will be set against the tension of the spring 34, in its retracted position shown in Fig. 1. When the releasing lever 41 is moved against the tension of its spring 42, the lever 39 will be released and this, of course, releases the batter, and the impelling spring 34 will then rotate the batter on its vertical pivot 30, under which movement the bat 33 will be swung horizontally forward. When the bat is properly set, it will move forward with a swinging movement on the line that will intersect the trajectory of the thrown ball, but to cause 105 the bat to strike the ball, the batter must be released at the proper time in respect to the release of the pitcher, and this will be found to require considerable skill.

In Fig. 1, the numeral 43 indicates one of 115 several blocks which may be placed on the bases to indicate the assumed position of the runner of the bases.

In playing the game of baseball, with the device arranged as above described, most of 120 the customary rules of the game may be followed. This is so for instance, as to the number of strikes required to put the assumed batter out. The person who is actually put out, being, of course, the person 125 who is manipulating the toy batter by means of the releasing lever 41. The same person may manipulate both the pitcher and the batter, or one person may manipulate the pitcher and the other the batter. As arbit- 130

trary rules of this game, when the batted ball strikes either the toy pitcher, short-stop, basemen or a fielder, the ball should be assumed to have been caught, and hence, 5 the batter to have been put out. If the ball stops within the diamond, a one base hit should be allowed; if the ball stops within the field zone *a*, a two base hit should be allowed, if the ball stops within the field 10 zone *b*, a three base hit should be allowed; if the ball stops within the field zone *c*, a four base hit or home-run should be allowed; and if the ball stops any other place, it 15 should be called a foul.

15 Any desired number of persons may play the game by the use of the device, and if desired, tripping and releasing levers for the pitcher and batter may be provided at both sides of the field plate 1, or one thereof 20 may be applied at one side of the plate, and the other at the other side thereof.

The hands of the catcher, as is obvious, 25 constitute a ball receptacle which is arranged to catch and hold the pitched ball. Furthermore, it is very important to note 30 that this ball receptacle is located above the floor, so that it is adapted to catch the pitched ball at a point above the floor. The pitched ball, if not struck by the batter, passes from the pitcher into the hands of the catcher without ever striking the floor and the floor forms no part of the ball receptacle.

What I claim is:

1. In a toy ball game apparatus, a pitcher, 35 a batter and a catcher, the said catcher having a ball receptacle located above the floor and arranged to catch the ball thrown by the said pitcher, at a point above the floor, and means for imparting pitching movements to said pitcher and batting movements to said batter.

2. In a toy ball game apparatus, a pitcher, 40 a batter and a catcher, the said pitcher being

arranged to throw the ball above the floor and the said catcher having hands forming 45 a ball receptacle located above the floor and adapted to catch the pitched ball at a point above the floor, and independently operated means for imparting pitching movements to said pitcher and batting movements to said 50 batter.

3. In a toy ball game apparatus, a pitcher, 55 a batter and a catcher, the said pitcher having an arm mounted for ball-throwing movements and for adjustments in a vertical plane, and said catcher having a ball receptacle located above the floor and arranged to catch the pitched ball at a point above the floor, and means for imparting 60 pitching movements to said pitcher and batting movements to said batter, substantially as described.

4. In a toy ball game apparatus, a pitcher, 65 a batter and a catcher, said catcher having a pair of hands forming a ball receptacle located above the floor, adapted to catch the pitched ball, and the said hands being spring-pressed together and adapted to be forced apart by downward pressure thereon from the ball, whereby the said ball 70 may be forced from said ball receptacle by downward pressure.

5. In a toy ball game apparatus, a pitcher, 75 a batter and a catcher, said catcher having pivoted frictionally held vertically adjustable arms with hands arranged to catch the pitched ball, and independent means for imparting pitching movement to said pitcher and batting movement to said batter.

In testimony whereof I affix my signature 80 in presence of two witnesses.

JOHN A. EKELUND.
